UNITED STATES PATENT OFFICE.

JOSEPH F. DONAHUE, OF PROVIDENCE, RHODE ISLAND.

GEM SETTING.

Application filed December 10, 1921. Serial No. 521,508.

To all whom it may concern:

Be it known that I, JOSEPH F. DONAHUE, a citizen of the United States, residing at Providence, in the county of Providence and 5 State of Rhode Island, have invented certain new and useful Improvements in Gem Setting, of which the following is a specification.

This invention relates to a jewelry component, more particularly to an improvement in the construction of settings for gems, and the object of this invention is to form such a gem-setting of a channeled member in which the edges of the side walls 10 of the channel are beveled to provide a seat for gems, and the edges of the walls formed thin and adapted to be bent over the opposite edges of the gems to bind them in the setting.

With these and other objects in view, the invention consists of certain novel features of construction, as will be more fully described, and particularly pointed out in the appended claims.

In the accompanying drawings.

Figure 1 is a face view of the gem-setting showing the hollow or open-centered frame or body having a channeled outline into which the gems are set.

Figure 2 is a face view of the sheet stock cut into the desired outline and having its center punched out, the dotted lines showing the width of the channel where the side walls are drawn up to form the channel.

Figure 3 is a greatly enlarged top view showing a portion of the channeled frame.

Figure 4 is a greatly enlarged section on line 4—4 of Figure 3, showing the edges as beveled and formed thin and so adapted to be bent over the edges of the gem.

Figure 5 shows the gem supported on the beveled side of the frame with the edges of the latter bent thereover to bind the gems in the setting.

The old method of forming multi-sided settings of the channeled frame type was to saw grooved wire ordinarily carried in stock, into sections and solder their mitered ends together but this was found to be too expensive and did not produce a finished article. The next method was to try to bend a length of this channeled, stock wire or strip, but this was found to be quite impractical owing to the fact that bending the wire into multi-sided figures having sharp

angles, the wire became crushed and its walls greatly distorted. As the first method of forming in section is too expensive, and the second is quite impracticable particularly where the devices are made small I have provided a new construction of channeled frame or body which is produced by drawing up a single piece of sheet metal, in a single operation, having a continuous channel and formed complete without the use of solder, which construction has many advantages over the structures formed by the old methods, and the following is a detailed description of one form of my improved device:—

With reference to the drawings, 10 designates a hollow or open-centered frame or setting which is constructed from a sheet-metal blank 11, see Figure 2, that is first cut from sheet stock into the desired outline with its center 12 removed. This blank is then struck with a hollow tool, shaped in outline similar to that shown in dotted lines 13 in this Figure 2 and when struck with this tool the side walls 14 of the frame or body are drawn up as illustrated in Figure 4 forming a continuous channel completely around the frame into which the gems 15 may be set.

The inner edges 16 of the walls of this channeled frame are preferably beveled as best illustrated in Figure 4, and these edges are formed very thin to be readily bent. The beveling of these edges may be produced by first striking the edge of the blanks if desired before being drawn up in channel form, or these edges may be beveled by running a cutting tool about them, or any other suitable means for beveling may be employed.

In mounting the gems in this channeled setting, I first deposit the gems one at a time into the channel with the edges of the gem resting against the beveled edges of the comparatively thin side walls 14 as shown in dotted lines in Figure 4, I then turn the extremely thin edges 17 of the side walls over the edges of the gems firmly securing them in the setting.

These gems by my improved construction 105 may be slid along on their beveled seat in the channel so that their edges will closely contact with each other producing the appearance of a continuous blaze of brilliancy completely about the whole setting. 110

I have shown a channeled setting of octagon shape but the same may be formed in any desired shape in outline.

By my improved construction a setting 5 may be struck up very rapidly and where the edges are formed thin by a swaging operation, when the blanks are dropped from the press they are practically complete and ready to receive the gems, and when so 10 set they are extremely strong and durable and yet handsome and attractive in appearance.

The foregoing description is directed solely towards the construction illustrated, 15 but I desire it to be understood that I reserve the privilege of resorting to all the mechanical changes to which the device is susceptible, the invention being defined and limited only by the terms of the appended 20 claims.

I claim:

1. A gem-setting comprising a continuous 25 seamless integral channel frame formed of sheet stock with a bottom portion and two opposite substantial parallel bendable side

walls standing upwardly therefrom forming a continuous channel, whereby gems of varying diameters may be longitudinally adjusted while being set to cause their margins to closely abut, the edges of said walls being provided with a continuous beveled seat for the gems, the thin edges of said beveled walls being adapted to be folded over the edges of the gems to bind them in their different set positions in the setting. 30

2. A gem-setting comprising an open centered one-piece seamless angular frame having a bottom forming the back of the frame and two spaced apart side walls folded to stand upwardly from said bottom forming a continuous channel, the inner edges of said walls having a continuous bevel along their length to provide a continuous seat on which the gems may rest and be longitudinally adjusted in setting, the outer portions of 40 beveled edges being formed thin to be readily folded over the edges of the gems to bind them in setting. 45

In testimony whereof I affix my signature.
JOSEPH F. DONAHUE.
